UNITED STATES PATENT OFFICE.

HERBERT RUSSELL NEVENS, OF HARTFORD, CONNECTICUT, ASSIGNOR TO NEVENS-WALLACE TRAIN CONTROL COMPANY, A CORPORATION OF MASSACHUSETTS.

RAILWAY SIGNALING DEVICE.

1,174,023.

Specification of Letters Patent.

Patented Feb. 29, 1916.

Application filed April 18, 1913, Serial No. 761,902. Renewed July 20, 1915. Serial No. 41,018.

To all whom it may concern:

Be it known that I, HERBERT R. NEVENS, a citizen of the United States, residing at Hartford, county of Hartford, State of Connecticut, have invented certain new and useful Improvements in Railway Signaling Devices, of which the following is a specification.

This invention relates to the positive control of railroad trains and the like, for the purpose of preventing the neglect or disobedience of the usual signals employed in such systems.

The invention is particularly adapted to be used in block systems where trains are to be kept absolutely within certain block limits.

The present invention is an amplification of the principles set forth in several prior applications on train controlling mechanism filed by me, and consists chiefly in various improvements and modifications of the devices disclosed in said applications.

In the further discussion of my invention I shall consider the improvements from two viewpoints of installation, namely, the single track installation and the double track installation.

In the single track installation two sets of signal boxes are used in a single block of track, one at each end of the block and on the opposite sides of the track. Each box arm has a pawl disposed for actuation by the wheels of the passing train, which pawl is effective to set the brakes when struck by a train traveling in the direction of the current of traffic and is ineffective when struck by a train traveling in the opposite direction, or against the current of traffic, as when backing up. A train entering a block in the direction of the current of traffic will, therefore, set that block upon its exit therefrom to protect its rear end and will also, at the same time, set the block in advance to protect its head end, in the event that a train should be approaching in the opposite direction. It is necessary, therefore, on single track roads that a tripper be disposed at each end of a block and on opposite sides of the track so as to control both directions of travel. These pawls point in opposite directions, that is to say, the pawl at the right side of the track, on which side

the brake setting mechanism of the engine is carried, and the signal arms of the block system are disposed, is pointing toward the current of traffic and in the direction of approach of the train, and the pawl at the left side of the track is pointing toward a train approaching from the opposite direction or against the current of traffic. The use of a pawl effective in one direction and ineffective in the other overcomes the liability of a train stopping itself on a clear block when passing the pawl on the left side of the track or in passing the rear side of a signal arm on the left of the track. This arrangement is especially desirable in places where traffic is congested and the stops must be close together to allow the backing of trains against the current of traffic by signal. It, moreover, obviates the use of a divide in the track circuit.

Considering briefly the double track installation. In this form the signal box is always on the right side of the track at the entrance to a block and there is no box on the left side of the track at the exit from the block. In the event that a reverse movement is desired, the trains are necessarily run against the current of traffic and there is virtually no signal control. They will, therefore, pass the pawl without being stopped. Should it be found necessary or desirable, however, it is always possible to install a signal box at each end of a desired block on opposite sides of the track as in the single track installation.

The construction and principle of my invention will be more fully disclosed in the specification which follows and as illustrative of the same I have shown in the accompanying drawings an embodiment which I have found practical and well adapted for the purposes intended.

Throughout the specification and drawings like characters of reference are employed to indicate corresponding parts and in these drawings:

Figure 1 is a plan view of a single track installation, showing five track sections or blocks. Fig. 2 is a longitudinal section through one of the signal boxes showing the pawl in its normal or interfering position. Fig. 3 is a similar view showing the pawl depressed into non-interfering position.

Fig. 4 is a plan view of one of the boxes with the cover removed to show its detailed construction. Fig. 5 is a longitudinal section on the line 5—5 of Fig. 4, the pawl being in non-interfering position. Fig. 6 is a section at right angles to Fig. 5, the pawl being shown in interfering position. Fig. 7 is a detail of the pawl. Fig. 8 is a vertical section on the line 8—8 of Fig. 7, and Fig. 9 is a detail section of a slightly modified construction of pawl.

For the purposes of explanation I have illustrated five sections or blocks of track lettered A, B, C, D, E, in Fig. 1. These 15 blocks are insulated from each other at *a*, *b*, *c*, *d*, and on account of the limited space are shown very short although it will be understood that each section is intended to represent a block of more than a train 20 length in extent. It will also be understood that I place a signal box at the entrance and exit of each block and on opposite sides of the track in a single track installation, although only two boxes are here shown on 25 account of the limited space and the necessity for adequately illustrating the wiring of the respective blocks.

At the right hand side of the track, near the entrance to the block B, I mount my 30 tripping mechanism which may be supported on two ties T. A similar mechanism is of course mounted on the opposite side of the track at the exit of said block. This tripping mechanism comprises in the preferred embodiment a tripping pawl 1 disposed adjacent to the rail and within the operative influence of the train wheels. This pawl is approximately right triangular in shape and has its inclined face or hypotenuse 2 disposed so as to be rigid when struck by the wheel of a train traveling 35 against the current of traffic, and its leg 3 set vertically with respect to the ties and yieldable when struck by the wheel of a train traveling with the current of traffic. The lower portion 4 of said pawl is formed as a weighted counter-balance to cause the pawl to right itself after being struck. Said pawl is mounted upon the wrist pin 5 of a rocker arm 6 which arm is chambered to receive the inner end of said pin. Arranged in said chamber and rigid on said wrist pin is a segmental rack 7 the teeth of which are adapted for engagement with the teeth of a 40 rack rod 8 mounted in said chamber and normally held in extended position by a coil spring 9 mounted in a bore in the rocker arm 6. When the inclined face 2 of the pawl is struck a practically rigid surface will be 45 presented to the wheel, a slight play being of course allowed to prevent stripping of gear teeth. When the vertical face 3 is struck the pawl will yield, the rotation thereof forcing the rack rod back against

the coil spring, compressing said spring in 65 its movement. This spring will, therefore, exert its tension to return the rack rod and pawl to its normal position after each wheel has passed.

The rocker arm 6 is fastened upon a transverse rock shaft 10 inclosed in a sleeve 11. This shaft is journaled in bearings in a box or housing 12 having its cover hinged at 13 and adapted to be locked at 14 by an ordinary padlock. Inclosed in said housing and pivoted on said shaft is a depending link 15, the free end of which is bifurcated to provide ears 16 adapted to fit over the longitudinally movable block 17, which block is chamfered on each side to form shoulders adapted to confine the ears of the link and act as stops or abutments to prevent the disengagement of the link from the block. Threaded in said block at its inner end is a short stem 18 the opposite end of which is slidable in the bore of a bearing 19 threaded in to a boss 20 projecting horizontally from the housing. A spring 21 surrounds said stem and is confined between the bearing 19 and the end of the block. Said spring is normally under compression, that is, when the pawl is in interfering position the block will be forcing the stem into the bore of the bearing 19 and thereby compressing the spring. In the opposite end of the block is threaded the inner end of a long stem 22 axially alining with said short stem 18 and carrying a lock nut 23 on its inner end. The outer end of said stem is slidable in the bore of a bearing 24 threaded into a boss 25 projecting horizontally from the housing and is controlled by a spiral spring 26 coiled thereabout and confined between the inner end of the bearing and the nut 23. The block 17 is therefore in the nature of 105 a turn buckle and permits a relative adjustment of the stems 18 and 22, while the tension of the spring 26 may be regulated by screwing up on the lock nut 23. The threaded bearing plugs 19 and 24 also permit relative outside adjustment of the parts. 110

Fastened to the rock shaft to move with the movement thereof are the arms 27 of a yoke shaped frame, the free ends of which are joined by a weighted arm 28 normally holding the pawl in the position illustrated in Fig. 2, and when in this position resting on a buffer 29 supported on the housing. 115

With the parts in the position shown in Fig. 2 the tendency of the pawl would be to 120 operate the brake system of the train irrespective of the condition of the track, *i. e.* whether it was safe or unsafe for the passage of the train. Inasmuch as it is not desirable to have this tripper effective unless there is already a train in the block C, I therefore provide a holding mechanism for maintaining the trip in the depressed posi- 125

tion shown in Fig. 3 when the block C is unoccupied, which locking mechanism is automatically released by the exit of the train from the block B into block C to return the 5 trip to interfering position and protect the rear end of the train. This locking mechanism comprises a pair of magnets 30 supported on brackets 31 rising from the floor of the housing. The adjustment of these 10 magnets is had by means of a pair of milled nuts 32 threaded into a post 33 adjustable relative to said magnets. The magnets are wired up in a normally closed electrical circuit and are always energized if there is no 15 train in the block C. An armature 34 is carried on the lower end of a vertically disposed lever 35 pivoted at 36 in brackets 37. Inasmuch as the magnets are normally energized, the lever 35 is held in the vertical position shown in Fig. 3. In this position the 20 notch 38 of said lever is disposed so as to be engaged by a shoulder 39 on the cross arm 28 whenever said cross arm is raised sufficiently for this purpose. This raising is effected by the passage of the first train wheel 25 over the pawl. As soon as the pawl and therefore the rock arm 6 is depressed by a wheel the yoke arms 27 are raised, lifting the cross arm 28 to the level of the notch 38. 30 Inasmuch as the lever 35 is already in position to support the cross arm when said arm is raised, the notch 38 catches the edge 39 of the cross arm to lock it in raised position. When the cross arm is locked the pawl will 35 be held in the depressed position shown in Fig. 3 as long as the magnets remain energized. The magnets are connected in circuit with the rails of the section C. A simple electrical circuit (see Fig. 1) comprises 40 lead wires 40 and 41 leading from the windings of the magnets to each of the rails of the block C. Also connected to said rails are the lead wires 42 and 43 of a battery 44. The block C is therefore a closed circuit 45 in which the magnets are included. When a train enters said block, however, the current is bridged across the rails by the wheels and axle of the train thereby cutting out the magnets. 50 In Fig. 9 I have shown a slightly modified construction of pawl. In place of the toothed segment 7 I mount on the stud 5 a toothed disk 45, the teeth of which are adapted for engagement with the teeth of a 55 pair of rack rods 46 and 47 arranged in superimposed relation to each other and on opposite sides of the disk. Said rack rods are held in their normal position by a pair of coil springs 48 and 49 respectively, said 60 springs being of different stiffness. In the operation of this form of pawl a train striking the inclined face 2 thereof unlike the type shown in Fig. 7, will slide the rack rods longitudinally against their springs. The

spring 48 against which the upper rack rod 65 46 bears, is stiff enough to set the tripper carried by the engine and thus apply the brakes. When a train coming from the opposite direction strikes the vertical face 3 of the pawl, the pawl will yield to the impact 70 and the rack rods will be moved inwardly against said springs. The spring 49 however, is not stiff enough to influence the 75 brake setting mechanism of the train and only serves to return the pawl to its normal position after each impact. It is here desirable to state that the weight on the pawl and the long arm in the box will throw the trip into danger of stopping position should any of the springs break. 80

The operation is substantially as follows: The normal position of the parts is that shown in Fig. 2 in which the pawl is pointing in the direction of approach of the train and is in position to be influenced by the 85 wheels. When the block C is clear, the magnets will be included in the circuit through the track battery and rails of said block and will therefore be energized to hold the locking lever 35 up in position to be engaged by the cross web 39 of the weighted yoke 27. The first wheel of a train entering the block B depresses the pawl against the action of the spring 26 and rocks the cross arm 28 up sufficiently to engage its web 39 90 with the notch 38 of the lever 35. This locks the pawl in depressed position so as not to contact with the tripper of the brake setting mechanism carried by the train. The pawl remains in depressed position until the train has passed into the block C whereupon the magnets will be cut out by reason of the wheels and axle bridging the current across the rails of said block. The deenergization of the magnets releases the 100 armature 34 and the lever 35 drops by gravity. The support for the cross arm 28 being thus removed the weight drops, raising the arm 6 and bringing the pawl up into interfering position so as to protect the 105 train now in the block C against rear-end collision. As soon as the train in block C passes out of said block, the circuit through the magnets is reestablished and the magnets are again energized. This puts the 110 lever 35 in condition to support the weight 29 when said weight is again raised. The pawl at the exit of the block (on the left hand side of the track) is always in interfering position relative to the wheels but will yield 115 to the impact by reason of its toothed segment and movable rack rod, its spring serving to return it to interfering position after each actuation. The pawl is therefore obviously incapable of interference except to 120 a train entering from the opposite direction or against the current of traffic. This protects the train from a head on collision. 125

Should block C already be occupied by a train proceeding in the direction of traffic (it being of course impossible under ordinary conditions for a train to enter said block past the exit covering pawl against the current of traffic) any train approaching block C will, therefore, find the entrance covering pawl in interfering position so that when a wheel contacts with it, said pawl 10 will be depressed by the wheel but will rise again immediately behind the wheel to trip the brake setting mechanism carried by the engine. This tripping mechanism for setting the brakes and stopping the train may 15 be of any desired construction as that set forth in the application filed by me June 19, 1911, serially numbered 634,010. It is obviously impossible for the locking lever to engage the notch of the yoke and lock the 20 pawl in depressed position when the block C is occupied, since the magnets are deenergized and the spring 26 is exerting its tension to urge the pawl back to its interfering 25 position. The train will, therefore, be stopped at the entrance to said block.

It will thus be seen that my device constitutes a positive stop for a train approaching a block already occupied or in which the circuit is broken through an accident to 30 the rails and that not only is the rear end of the train protected, but provision is made for preventing the entrance in the block of a train approaching from the opposite direction.

Various modifications in the construction 35 and form of my invention coming within its scope and spirit, may obviously be resorted to if found within the limits of the appended claims.

What I, therefore, claim and desire to 40 secure by Letters Patent is:

1. In a tripping mechanism, a tripper, a gravity operating member therefor, a gravity lock normally disposed in the path of 45 said member in supporting relation thereto, and independent electrically controlled means having an engaging relation with said lock effective to move said lock into position to support said gravity member and having a disengaging relation with said 50 lock effective to allow said lock to fall by gravity out of supporting position relative to said gravity operating member.

2. In train control mechanism, insulated 55 track sections, a trip in each section normally positioned in interfering relation to the wheels of a passing train, a normally closed electrical circuit establishing communication between a trip and an adjacent track section, means included in said circuit normally effective to lock said trip in non-interfering position after contact of the first train wheel with said trip, and means to 60 return the trip to interfering position when

the circuit to said locking means has been 65 broken by the passage of the train past said trip and into said adjacent section.

3. In a tripping mechanism, a pivoted tripper, a gravity member operatively connected with said tripper, and effective to 70 maintain said tripper in actuating position, a pivotal support for said gravity member having a supporting and a non-supporting position and normally disposed in the path of said gravity member to support the same, 75 an armature carried by said pivotal support, and an electro-magnet associated with said armature and having a normal engaging relation with said armature, effective to maintain said pivotal support in its supporting 80 position relative to said gravity member and having a disengaging relation with said armature effective to allow said support to assume its non-supporting position relative to said gravity member. 85

4. In a tripping mechanism, a tripper, a weighted operating member therefor, a gravity lock for said member normally disposed in the path of said operating member and in supporting relation thereto, an armature movable with said lock and an electro-magnet associated with said lock and having a normal engaging relation with said armature effective to maintain said lock in 90 position to support said operating member and having a disengaging relation with said armature effective to allow said lock to fall by gravity out of supporting position relative to said operating member. 95

5. In a tripping mechanism, a pivoted 100 tripper, an actuating counterweight operatively connected with said tripper and effective to maintain said tripper in actuating position, a pivotal support for said counterweight having a supporting and a 105 non-supporting position and normally disposed in the path of said counter-weight to support the same, an armature movable with said pivotal support, and means having an engaging relation with said armature effective to move said support into its counterweight supportive position and having a disengaging relation with said armature effective to allow said pivotal support 110 to fall by gravity into its non-supporting 115 position relative to the counterweight.

6. In train control mechanism, a trip actuating member normally positioned in interfering relation to the wheels of a passing train and arranged to be displaced by 120 contact with the first train wheel from its position of interference to one of non-interference, a locking mechanism normally effective to lock said member in non-interfering position immediately after its displacement by the first train wheel and ineffective to lock said member in non-interfering position when it is desired to stop the train, 125

and a control for said locking mechanism normally effective to allow said locking mechanism to be released and the trip-actuating member to return to interfering position as soon as the train passes beyond the limits of said control.

7. In train control mechanism, insulated track sections, a trip normally positioned in interfering relation to the wheels of a passing train, a rock shaft operatively connected with said trip, means associated with said shaft normally effective to assist in maintaining said trip in interfering position, including a gravity operating member, a locking member positioned for engagement with said gravity operating member, an armature movable with said locking member, an electro-magnet associated with said armature, and a normally closed electrical circuit 20 from said magnet to an adjacent track section and normally effective to put said locking member in condition to lock said gravity operating member and maintain the trip in non-interfering position after contact of the 25 first train wheel with said trip.

8. In a train control mechanism, insulated track sections, a trip normally positioned in interfering relation to the wheels of a passing train, a rock shaft operatively connected with said trip, a gravity operating member, normally effective to assist in maintaining said trip in interfering position, a pivotal support for said member having a supporting and a non-supporting position and 30 normally disposed in the path of said gravity member, and a control for said pivotal support effective to move said support into position to support said gravity member when it is not desired to stop a train and 35 effective to permit said pivotal support to assume its non-supporting position relative to the gravity member when it is desired to stop a train.

9. In train control mechanism, insulated track sections, a trip normally disposed in interfering relation to the wheels of a passing train and arranged to be displaced from its position of interference to one of non-interference by contact with the first train 50 wheel, a gravity operating member associated with said trip, a pivotal support for said member having a supporting position effective to engage said gravity member and lock the trip in non-interfering position immediately after contact of the first wheel 55 with the trip and having a non-supporting position ineffective to lock the trip, and an electrical control for said pivotal support normally effective to move said support to its supporting position.

10. In train control mechanism, track sections, a trip normally disposed in interfering relation to the wheels of a passing train, a rock shaft operatively connected

with said trip, a pair of spring controlled stems operatively connected with said shaft, a balance member connected with said shaft, a locking member positioned for locking engagement with said balance, and an electrical circuit controlling said locking member 65 and normally effective to move said locking member into position to lock said balance member after contact of the first train wheel with the trip.

11. In train control mechanism a trip, a rock shaft operatively connected with said trip, a link on said shaft, a pair of stems connected with said link, springs of different tension controlling said stems, a balance member connected to said rock shaft, a locking member, and a control normally effective to move said locking member into position to lock said balance member.

12. In train control mechanism, a track trip mounted for contact with the tripper of a train carried brake-setting mechanism, means normally effective to maintain said track trip in interfering relation to the wheels of a train, said means being overcome by the displacement of said track 85 tripper by the first train wheel from its position of interference to one of non-interference, and means becoming effective upon the displacement of said track tripper to positively maintain said trip in 90 non-interfering position to permit the unobstructed passage of the train carried tripper past said track trip.

13. In train control mechanism an insulated track section, a track trip mounted in 100 said section for contact with the tripper of a train carried brake-setting mechanism, means normally effective to maintain said track trip in interfering relation to the wheels of a train passing through said section, said 105 means being overcome by the displacement of said track trip by the first train wheel from its position of interference to one of non-interference, and gravity operating electrically controlled means becoming effective upon the displacement of said track trip to positively maintain said trip in non-interfering position as long as the train is in said section to permit the unobstructed passage of the train carried trip past said 110 track trip and ineffective to lock said track trip in non-interfering position when it is desired to stop a train.

14. In train control mechanism, insulated track sections, a track trip in one of said 120 sections mounted for contact with the tripper of a train carried brake-setting mechanism and normally disposed in interfering relation to the wheels of a passing train and normally displaceable from said position of interference to one of non-interference by the first train wheel to permit the unobstructed passage of the train carried

tripper therepast, and means effective when it is desired to stop the train to positively maintain the track trip in wheel interfering and tripper contacting position whereby the track trip is displaced by the first train wheel and returns immediately behind the wheel to actuate the train carried tripper.

In testimony whereof I affix my signature in presence of two witnesses.

HERBERT RUSSELL NEVENS.
